(57) **CLAIM**

The ornamental design for decorative feet, as shown and described.

DESCRIPTION

FIG. 1 is a front side view of the decorative feet of the new design.

FIG. 2 is a lateral view of the right side of the decorative feet of the new design. The lateral view of the left side is identical; and,

FIG. 3 is an overall perspective view of the decorative feet of the new design.

The broken lines shown in the drawings are included for the purpose of illustration and form no part of the claimed design.
